(57) CLAIM

What is claimed is the ornamental design for an undergarment, as shown and described.

DESCRIPTION

FIG. 1 is a perspective view of an undergarment;
 FIG. 2 is a front view thereof;
 FIG. 3 is a rear view thereof;
 FIG. 4 is a left side view thereof;
 FIG. 5 is a right side view thereof;
 FIG. 6 is a top view thereof; and,
 FIG. 7 is a bottom view thereof.
 The components in broken lines depict environmental subject matter only and form no part of the claimed design.
